JEWELRY CASE OR SIMILAR ARTICLE

Martin A. Jaffe, 3001 Henry Hudson Parkway, Bronx,
N.Y. 10463; George S. Northrop, 3200 Hickory St.,
Wantagh, N.Y. 11793; and Samuel Braun, 75 Green-
haven Road, Rye, N.Y. 10580

Filed Aug. 12, 1970, Ser. No. 24,443

Term of patent 3½ years

Int. Cl. D3—99

U.S. Cl. D87—1

FIG.1

FIG.2

FIG.3

FIG.4

FIG. 5

FIG. 6

FIG. 7

FIG. 1 is a front elevational view of a jewelry case or similar article, showing our new design;

FIG. 2 is a top plan view;

FIG. 3 is a bottom plan view;

FIG. 4 is a rear elevational view;

FIG. 5 is a side elevational view with the cover open;

FIG. 6 is a top plan view with the cover open; and

FIG. 7 is a sectional side elevational view taken along line 7-7 of FIG. 6.

The surface characteristics that are fragmentarily shown in FIGS. 1-6 are typical for substantially the entire outer spherical surface.

We claim:

The ornamental design for a jewelry case or similar article, as shown and described.
